UNITED STATES PATENT OFFICE.

WILMAR F. LENT, OF NEW YORK, N. Y., ASSIGNOR TO THE CUTLER-HAMMER MFG CO., OF MILWAUKEE, WISCONSIN, A CORPORATION OF WISCONSIN.

MOTOR-CONTROLLER.

1,347,863.

Specification of Letters Patent. Patented July 27, 1920.

Application filed June 21, 1916. Serial No. 104,841.

To all whom it may concern:

Be it known that I, WILMAR F. LENT, a citizen of the United States, residing at New York, in the county of New York and State 5 of New York, have invented new and useful Improvements in Motor-Controllers, of which the following is a full, clear, concise, and exact description, reference being had to the accompanying drawing, forming a 10 part of this specification.

This invention relates to motor controllers.

In the control of motor driven planers it is essential to insure against drifting of 15 the planer bed through its limits upon failure of voltage or the tripping of circuit breakers, and this invention has among its objects to provide for planers and other devices efficient and reliable braking means 20 to meet such contingencies.

Further, the invention has for an object to provide means for effecting dynamic braking of planers and other automatically reversible devices by their driving motors 25 regardless of the operation of the reversing means of such motors, as at the limits of a planer.

Other objects and advantages of the invention will hereinafter appear.

30 One embodiment of the invention is diagrammatically illustrated in the accompanying drawing and the same will now be described, it being understood that the invention may be embodied in other forms falling within the scope of the appended claim.

The controller shown in the accompanying drawing is particularly applicable to planers and to the special type of driving motor M illustrated, said motor including 40 an armature a, a series field winding f, an interpole winding f' and a shunt f".

The controller is in general of conventional form. It includes an electro-responsive main switch 1, and a mechanical device 45 including reversing switches 2 and 3 and accelerating switches 4, 5, 6 and 7. The reversing switches are operable selectively by a cam shaft 8 manually operable at will and also adapted to be connected to the planer for 50 reverse operations at the limits thereof, while the switches 4 to 7 are operable in progression by a cam shaft 9 under the control of shaft 8. The shaft 9 is operable by a weight 10 to close the switches and by 55 shaft 8 through a link 11 to open said

switches, the arrangement being such as to insure the opening of said switches upon initial closure of either reversing switch while thereafter permitting said accelerating switches to close automatically. Accelerating switches 4, 5 and 6 control resistances r, r' and r² for the motor circuit while the switch 7 controls a short circuit around the series field f and a resistance r³. The mechanical controller also includes auxiliary 60 switches 12 and 13, the former providing an interlock between said controller and the main switch and the latter controlling a short-circuit around field rheostats 14 and 15. The switch 13 normally closes the short- 70 circuit around the field rheostats and is operable by cam shaft 9 to interrupt said short-circuit after closure of the accelerating switches. The rheostats 14 and 15 are further controlled by auxiliary contacts 2^a and 75 3^a of reversing switches 2 and 3 respectively to utilize the same selectively for reverse operations of the planer. Still further, the controller includes a normally open push button switch 16 to energize the main switch 80 1 at will and a normally closed push button switch 17 to deenergize the main switch at will.

The control means described thus provides for setting the motor in operation and 85 automatically reversing the same at the limits of movement of the planer bed, such reversals being effected by reversal of the flow of current through the motor armature. Accordingly under normal conditions 90 the power operation of the motor restrains the planer against over-travel. But in the event of failure of voltage or operation of the usual circuit breakers (not shown) such restraint by the motor is lost with consequent danger of over-travel of the planer 95 bed. Such over-travel, however, is positively precluded by the control means which will now be described.

The main switch 1 is provided with down 100 contacts 1^a which when in engagement establish a local circuit across the terminals of the motor armature including a resistance r⁴. Also, the main switch 1 has associated therewith a normally closed auxiliary switch 105 1^b which establishes a local circuit across the terminals of the shunt field f" including a resistance r⁵. Switch 1^b is arranged to be engaged and opened by main switch 1 upon response of the latter to complete the motor 110

circuit and to reclose upon opening of said main switch. Further, the main switch has auxiliary contacts 1^c controlling the continuity of the shunt field circuit and serving 5 to interrupt said circuit to cause the shunt field to discharge through the local circuit provided therefor by switch 1^b. Still further, the main switch has auxiliary contacts 1^d to complete a maintaining circuit 10 therefor through a high resistance r^6 which resistance may be so proportioned as to effect opening of the main switch upon any desired drop in voltage, as for example, a drop to 80% of the normal line voltage.

15 Thus whenever the main switch opens it will establish a dynamic braking circuit for the motor and at the same time localize the shunt field discharge to maintain the excitation of said field. Accordingly if the main 20 switch is opened while the motor is in operation and the planer is between limits, the motor will have the full benefit of the heavy field discharge to maintain a strong field for dynamic braking. Moreover, even if 25 the planer should reach its limit before being finally stopped with a consequent reversal in the connections of the motor armature the heavy field discharge would more than offset any demagnetizing effect of such 30 reversal and insure continued braking action of the motor to bring the planer to a quick stop. In this connection it is also to be noted that if upon failure of voltage the counter voltage of the motor should tend to 35 hold the main switch closed such tendency would be eliminated at the limits of the planer bed by the interruption of the motor connections incident to reversal of the motor. The main switch would accordingly 40 open immediately to effect dynamic braking as described. On the other hand, so long as the planer bed does not drift to its limits the delay in the opening of the main switch is immaterial and in the case of a planer 45 the friction quickly reduces the speed of the motor and hence its counter voltage to a degree sufficient to effect release of the main switch according to the value of the resistance r^6 . Manifestly therefore an efficient 50 and reliable braking action by the motor is insured upon either failure of voltage, tripping of circuit breakers or operation of stopping switch 17 and regardless of the position of the planer or other driven device.

55 The circuit connections will now be described. With the line switch L, the main switch 1 and reversing switch 2 closed, circuit may be traced from line L' by conductors 20 and 22 through resistance r^2 , by conductor 60 23 through resistance r^3 and series field f, by conductor 24 through the right hand pole of switch 2, by conductor 25 through resistance r^1 , by conductor 26 through resistance r^4 , by conductor 27 65 through the interpole winding f' and ar-

ture α , by conductors 28 and 29 to and through the left hand pole of switch 2, by conductor 30 to and through main switch 1, by conductor 31 to line L². Also, circuit may be traced from line L by conductors 20, 70 32 and 33 through switch 13, by conductors 34 and 35 through the shunt field winding, by conductor 36 through contact 1^c of main switch 1 to conductor 31 and thence to line L². The connections thus provide for starting the motor with full field strength and it will be assumed that said connections effect operation of the planer in working direction. Following establishment of such connections the switches 4, 5 and 6 respond progressively to exclude the resistances r , r' and r^2 from the armature circuit and thereupon switch 7 responds to short circuit the series field and resistance r^3 by the connections which are obvious. Finally the switch 13 75 is opened whereupon the current supplied to the field is forced to take a path from conductor 32 by conductors 37 and 38 through the auxiliary contacts of switch 2, by conductors 39 and 40 through rheostat 80 14 to conductor 35 and thence through the field as already described. On the other hand, with the switch 2 open and switch 3 closed the armature connections are reversed and resistance r is excluded from 85 said connections. Under such conditions circuit extends from conductor 20 through resistances r^2 and r^3 and through the series field in the same direction as above described to conductor 24 and thence through the 90 right hand pole of switch 3 to conductor 28 and through the armature and interpole field in a reverse direction to that previously described, to conductor 27 through resistance r' , by conductor 26 through the left 95 hand pole of switch 3, by conductor 30 and thence through the main switch 1 to line L². The initial field connections are the same as described but when switch 13 is opened the field circuit is shifted to rheostat 15 instead 100 of rheostat 14. Under such conditions the field circuit extends from conductor 32 through rheostat 15 by conductors 41, 40 and 42 through the auxiliary contacts 3^a of switch 3, by conductor 43 to conductor 35 105 110 and thence through the field as described. The energizing circuit of main switch extends from line L' by conductor 20 to and through the auxiliary contacts 12 of the mechanical controller by conductor 44 through 115 push button switch 16, by conductor 45 through push button switch 17, by conductor 46 through the winding of main switch 1 to conductor 31 and line L². When, however, the mechanical controller operates it breaks 120 circuit at its contacts 12 thereby throwing the main switch onto its maintaining circuit. This maintaining circuit extends from line L' by conductors 20 and 47 through 125 resistance r^6 , auxiliary contacts 1^d of the 130

main switch, by conductor 48 to conductor 45 and thence through switch 17 and the winding of main switch 1 as already described. Accordingly should the main switch open while the mechanical controller is in running position it cannot be energized until such controller is returned to off position to reengage its auxiliary contacts 12.

The dynamic braking circuit established by the main switch varies according to the reversing switch which is closed at the time. With switch 2 closed the dynamic braking circuit may be traced from the right hand terminal of the motor armature by conductors 28 and 29 to and through the left hand pole of switch 2, by conductor 30 through down contacts 1^a of the main switch, and through resistance r^4 , by conductors 50 and 24 to and through the right hand pole of switch 2 and by conductor 25 through resistance r , by conductor 26 through resistance r' , by conductor 27 through the interpole field to the left hand terminal of the armature. On the other hand with the switch 3 closed the braking circuit may be traced from the right hand terminal of the armature by conductor 28 through the right hand pole of switch 3, by conductors 24 and 50 through resistance r^4 and the down contacts 1^a of the main switch, by conductor 30

through the left hand pole of switch 3, by conductor 26 through resistance r' , by conductor 27 through the interpole field f' through the left hand terminal of the armature. The field discharge circuit is independent of the reversing switches and may be traced from the right hand terminal of the field by conductor 36 to and through auxiliary switch 1^b of the main switch, by conductor 51 to and through resistance r^5 to the left hand terminal of said field.

What I claim as new and desire to secure by Letters Patent is:

In a controller for an electric motor having a shunt field winding, in combination, an electro-responsive switch responsive to establish power circuits for both the motor armature and shunt field winding and releasable upon failure of voltage to interrupt said circuits, means to increase the resistance of the circuit of said switch after response thereof to increase its sensitiveness to voltage reductions and means controlled by said switch to establish local circuits for the motor armature and shunt field windings upon interruption of their power circuits.

In witness whereof, I have hereunto subscribed my name.

WILMAR F. LENT.
